UNITED STATES PATENT OFFICE.

EVA J. GOLDENBLUM, OF NEW YORK, N. Y.

UNDERGARMENT.

Application filed June 27, 1927. Serial No. 201,636.

The present invention is concerned with the provision of a novel type of ladies' undergarment adapted to serve the three-fold purpose of a brassière, bodice, and bloomer.

5 An object of the invention is to provide a comfortable, unitary, form-fitting garment of this character which will be of extremely inexpensive construction, which will be neat and attractive in appearance, and which may 10 well serve as the sole necessary undergarment to be worn during warm weather; except of course, where a slip must be worn with a very sheer dress.

Other objects of the invention are to provide 15 a garment which will satisfy every sanitary requirement, and at the same time be quite modest, due to its bust-confining and concealing feature, and the closed crotch which it embodies.

20 Another and more specific object of the invention is to provide a unitary garment of the character noted above, having a side sanitary opening which will permit convenient manipulation of the garment for sanitary 25 purposes, and easy donning of the garment.

Another object is to provide a garment which may be selectively worn as a closed bloomer or as a step-in with the conventional side slits, the latter assuring coolness in warm weather.

Still another object of the invention is to provide a garment having means to permit the ready detachable connection of garters 35 including clasps for holding a sanitary bandage. In this connection, it is to be noted that the garment while substantially form-fitting, provides adequate room adjacent the crotch for accommodating a bandage without discomfort to the wearer and without distortion or staining of the garment; and that the side opening feature permits the ready application or removal of both the bandage and its detachable supporting means 40 without removing the garment itself.

With the above noted and other objects in view, the invention consists in certain novel features of construction and combinations and arrangements of parts, as will be 50 more fully hereinafter set forth and pointed

out in the claims. The invention may be more fully understood from the following description in connection with the accompanying drawings, wherein—

Fig. 1 is a front perspective view showing 55 my improved garment in applied position.

Fig. 2 is a rear perspective view thereof.

Fig. 3 is a fragmentary perspective view showing the garment opened on the side to disclose the side fastening means. 60

Fig. 4 is a perspective view taken from the other side, and showing the closed side of the garment partially unbuttoned to form a slit or step-in effect.

Fig. 5 is an enlarged sectional detail 65 through the garment crotch taken approximately on the line 5—5 of Fig. 4.

Fig. 6 is a transverse sectional view on the line 6—6 of Fig. 1.

Fig. 7 is a greatly enlarged sectional detail on the line 7—7 of Fig. 1.

Fig. 8 is a greatly enlarged sectional detail on the line 8—8 of Fig. 1.

In the drawings I have used the reference character 10 to designate generally the upper portion of the garment which serves as a combined brassière and bodice, and the reference numeral 11 to designate generally the lower drawers or bloomer portion of the garment. 75

The bodice 10 is supported by shoulder straps 12 and is adapted to snugly fit and confine the bust of a wearer in order to accentuate the boyish lines now in vogue. From the bust to the waistline, the garment is substantially semi-form fitting, allowing a certain comfortable freedom adjacent the waist. Incidentally, the garment while supporting and flattening the bust, allows more comfortable breathing than the ordinary brassière, due to the somewhat loose fit below the bust. The entire garment is preferably made of inelastic material. 85 90

In some instances, particularly where the garment is made of comparatively sheer material, I employ a modesty band 13 extending 95 across the front gore of the bodice. Preferably, the modesty band includes one or two laminations of the same material from which the body of the garment is made, and is attached at its ends only by the means of the 100

front gore; this modesty band extending directly across the bust and further aiding to confine the latter.

The lower drawers or bloomer portion of the garment snugly fit the wearer's hips, but the leg portions fit loosely at their lower ends, so that they will in no way confine or restrict bending movements of the wearer. Preferably, these drawers terminate somewhat above the knee, and are cut lower in the back to permit greater freedom of movement. The bodice formed of any suitable number of sections of material secured together by vertical lines of stitching, and the drawers which are similarly formed, are connected together by a waistline seam at 14 to provide a unitary garment.

As best seen in Fig. 3, the garment at one side may be open from the top to the bottom, the bodice opening being closed by separable fasteners such as the hooks and eyes 15 and the drawers opening at its lower end being closed by buttons 16 and buttonholes 17. There is further provided adjacent the hip, a supplemental closure in the nature of a button 18 and associated elastic strap 19.

The hooks and eyes are borne by strips 20; the hook-carrying strip being sewed to the outer face of the garment, and the eye-carrying strip being sewed to the inner face of the opposite end of the garment.

In this type of garment it is of course important that the uppermost fastener be arranged very close to the garment top. Inasmuch as it is somewhat difficult to provide a hook and eye at this precise point, I preferably employ a button 21 and elastic loop 22 at the upper edges of the opening, the loop 22 being preferably anchored in place by the same line of stitching which secures the eye-bearing strip 20, so that this strip and loop can be easily adjusted to accommodate different sized wearers.

For ordinary sanitary purposes, the hooks and eyes remain closed, and the two lower buttons 16 are opened. I have shown three of these buttons near the lower end of the garment. The elastic loop at 19 gives a certain amount of play when the garment is folded back for sanitary purposes, and also assures correct movement of the open garment flaps back to normal position when the wearer rises from a sitting posture. To adjust a bandage, all three buttons are opened. The three buttons at each side of the garment at the bottom, also give the garment a neat, tailored appearance.

Corresponding in location and arrangement to the buttons 16 are buttons 16^a and buttonholes 17^a at the outside of the opposite leg. By virtue of this arrangement, the drawers may either be worn with the side buttons closed, or the garment may be worn without buttoning the two sets of three buttons, in which instance it will simulate in

construction the ordinary step-in with a slit side. When thus worn, it is of course cool.

While the bloomers or drawers 11 fit rather snugly around the waist, the crotch is so designed as to provide the necessary fullness indicated in Fig. 5 for the convenient reception of a bandage 23. A feature of the invention is the provision of small inconspicuous tape loops 24 at both the front and rear median lines of the garment adjacent the waistband to which bandage supporting garters 25 including clasps 26 of conventional construction may be attached. The loops are of the proper size to prevent slipping of the safety pins which are connected to the garters. These garters are preferably secured by safety pins 27 or other convenient and conventional detachable securing means to the loops 24, so that the garters may be rapidly removed when not required, or when the garment is being laundered.

By clasping the two ends of the bandage 23 with the clasps 26, the bandage is securely and comfortably supported, and the operation of attaching or removing the bandage is not only rendered extremely convenient and expeditious, but also much more sanitary and pleasant than is the case where ordinary safety pins are used. This is particularly true when using bandages of the medicated cellulose texture now commonly employed, which frequently have a tendency to snag in the pins.

The fact that the garment may be fully opened at one side, also greatly facilitates and expedites the removal and attachment of both the garters and the devices which may be supported thereby.

Obviously, various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claims.

I claim:

1. A union undergarment of the class described including a body encircling portion adapted to confine the bust and fitting loosely from the bust to the waist, a drawers portion attached to the body portion at the waistline, said drawers portion snugly fitting the hips and at its lower end loosely fitting the wearer's legs above the knee, said garment having a side opening extending from top to bottom, strips of hooks and eyes secured to the body encircling portion of the garment along the edges respectively of the body opening to close the latter, and a button and elastic tape loop for closing the opening at the extreme top, said loop being secured by the line of stitches which holds one of the strips.

2. A union undergarment consisting of a

body encircling section, a drawers section attached to the body encircling section at the waist line, said garment having a side opening extending from top to bottom, cooperative fasteners secured respectively along the edges of the opening to substantially close the latter, a modesty band concealed by and ex-

tending across and secured to the front portion of the body encircling section, an elastic tape loop and a button respectively secured to top portions of the garment for the purpose of closing said garment at the extreme top. ¹⁰
